Filed July 10, 1956, Ser. No. 596,905

9 Claims. (Cl. 235—91)

This invention relates generally to counter mechanisms and more particularly to an improved form of counter device adapted to count and register individually a number of separate items and to totalize the values of such individual counts.

Though the present invention is of general application it is particularly adapted for use in the lumber industry to assist in filling orders for loads of lumber. Sales of lumber in this industry are made on the basis of board footage measure. To determine board footage it is necessary to ascertain the lineal footage of the lumber comprising the load. However, effecting this determination is burdensome since orders for lumber are conventionally filled by supplying lumber in random lengths, such lengths being in even number of feet and varying from one length size to the next larger by increments of two feet. To acquire knowledge regarding the various lengths in a load and the number of each of these lengths, it is the custom in the industry, as a load is being made up, to have a tally man present whose task is to count and make a pencil notation on a tally sheet of the pieces of lumber of each length as each piece is placed in the load. The tally man has no way of knowing when the proper amount of lumber has been accumulated and, therefore, must, at the time he believes the load to contain the footage ordered by the customer, halt the loading crew and make his computations. In this computing process he will multiply the number of pieces of each length, using the number he has pencilled on his tally sheet, by the number of lineal feet in that length and, thereafter, add has various totals to determine if the lumber present in the load is in accordance with the order. If the total is at variance with the required total then pieces must be added to the load if there is a deficiency, or subtracted from the load if there is an overage. Obviously, filling a load by this means is a laborious and time-consuming procedure and, clearly, is subject to arithmetical errors. Further, since there is chance for arithmetical error the tally sheet which is turned into the office by the tally man is checked by at least one other man and if error is found then the load must be disturbed.

It is, therefore, an object of this invention to provide a counting mechanism which can be used in the field to afford an accurate running piece-count, at all times, of the various lengths of lumber being placed in a load, and simultaneously an accurate aggregate total of the lineal feet present, so that a load of lumber may be quickly, correctly, and efficiently accumulated.

It is, further, an important object of this invention to provide an improved form of counting mechanism which will provide individual totals of a number of items and a cumulative total of the values of such items, which mechanism is rapid in its action, accurate in its information, and requires no undue effort in its operation.

Another object of this invention is to provide a counting mechanism which comprises a plurality of individual counters for providing information concerning indi-

2

vidual quantities of a number of items and a totalizing counter which is actuated simultaneously with each individual counter for indicating the total value of the individual quantities.

5 Another object of the invention resides in the construction of a counting device which is simple and durable, economical to manufacture, and which effectively and efficiently performs the purpose for which it was designed.

10 Other objects and features of the present invention will be readily apparent to those skilled in the art from the following specification and appended drawings illustrating a certain preferred embodiment in which:

Figure 1 is a top plan view of a counting device in accordance with the present invention.

Figure 2 is an enlarged, fragmentary, sectional view taken along the line II—II of Figure 1.

Figure 3 is an enlarged, vertical sectional view along the line III—III of Figure 1.

20 Figure 4 is an exploded view of the correcting assembly of the present device, and

Figure 5 is an exploded view of elements of the actuator assembly of the present device.

Having particular reference now to the drawings an illustrative embodiment of the present counting device is shown therein and is indicated in its entirety generally by the numeral 10. Counting device 10 comprises a counter actuator assembly 11, a plurality of counters 12, a summing or totalizing counter 13, and a reset arrangement 14, all supported by a casing or housing 15.

As shown in Figure 1 the counters 12, in the present embodiment, are arranged in two groups of six counters each, one group on either side of the centrally located counter actuator 11 and the individual counters of each group being in aligned arrangement relative to one another.

35 Casing or housing 15 includes a base 16 and a generally pan-shaped cover 17. Upon the cover 17 appropriate indicia are suitably painted or imprinted in association with the counters 12. Since the present embodiment is intended for use in the counting of lumber of variant length, the counters 12 are identified by numerals corresponding to usual or convenient lengths in which lumber may be sold. In the present case it will be assumed that the lumber to be counted is available in lengths ranging from 2 feet to 24 feet varying from each other by increments of two feet. It is understood that this invention is not limited to the particular number of counters shown but that any appropriate number may be employed dependent on the desired task or use to which the present counting device is intended. The number of counters 12 employed will correspond to the number of items or articles concerning which it is desired to maintain an accurate account.

45 Cover 17, generally centrally between its lateral sides, has a generally circular raised portion 18 die-cast or otherwise suitably formed therein and having an annular opening 19. Raised portion 18 includes a generally upright annular wall 21 having an inwardly directed flange 22 whose inner circular edge defines the annular opening 19. Upon the upper surface of inwardly directed flange 22 there is applied a circular series of even numbers from 0 to 24, generally indicated by the numeral 23, which numbers, as shown in Figure 1, are consecutively arranged in increasing order in a counter-clockwise direction from a stationary finger stop 25. Stationary finger stop 25 is located between the 0 and 24 numbers and is suitably secured at one end to the upper surface of flange 22 and projects into the space above opening 19.

60 65 70 Positioned in housing 15 for association with the series of numbers 23 provided on flange 22 is the counter

actuating assembly 11. Counter actuating assembly 11 comprises a rotatable drive structure or member 26 which operatively supports a plurality of rectilinearly movable block-like plungers or push-buttons 27.

Drive structure 26 is formed of a first circular plate 28, a disc-shaped member 29, and a second circular plate 31, with disk member 29 being disposed between plates 28 and 31 and these plates being secured to disk member 29 by a plurality of screws 32 whereby these three elements move as a unit.

First circular plate 28 is provided with a circular series of thirteen openings 33 located near the periphery of the plate and adapted to receive the finger of an operator. Disc-shaped member 29 is likewise afforded with a circular series of thirteen openings, which are numbered 34, located adjacent the periphery thereof through which plungers 27 extend, as will be described in detail hereinafter. The second circular plate 31 is provided about its periphery with a series of thirteen slots or openings 35 conforming in shape to the cross-sectional shape of plungers 27 for guidance thereof as will be further explained. With first plate 28, disc-shaped member 29, and second plate 31 secured in assembly, the openings 33, 34 and 35 thereof will be positioned in vertical alignment for slidably receiving the plungers 27.

Each plunger 27, as shown, comprises a block-like body portion 36 having an annular flange 37 adjacent its upper end and a cylindrical portion 38 projecting from its upper end. On the face 39 of body portion 36, below flange 37, is suitably affixed a generally L-shaped stop element 41 formed of resilient metal, whose shorter leg 42 is adapted to be moved into a recess 43 provided in face 39 in certain operations of plunger 27.

Below the stop element 41, face 39 of body portion 36 is transversely slotted as at 44 for a purpose to be described. From the opposite face 45 of body portion 36 at the lower end thereof there extends a projection or protuberance 46 adapted for effecting operation of a counter 12, as will be described.

As stated, plungers 27 are movably supported by drive member 26, Figures 2 and 3 showing the manner of mounting. As shown, each plunger 27 is located within a set of aligned openings 33, 34 and 35 and associated with each plunger is a spring 47 which is contained within opening 35 of disc-shaped member 29 and in surrounding relationship to body portion 26 of plunger 27. The lower end of spring 47 rests upon second plate 31 while the upper end thereof bears against flange 37 of plunger 27 to hold it in engagement with the lower surface of first circular plate 28. With flange 37 disposed against plate 28 cylindrical portion 38 of plunger 27 will project into opening 33 of plate 28 in position to be pushed by the finger of an operator. Flange 37, it is apparent, is of a size which permits its containment within opening 34 of disc-shaped member 29, but is of greater diameter than the openings 33 and 35 of plates 28 and 31 so that when these plates are affixed to disc-shaped member 29 plungers 27 cannot be removed from drive member 26. Springs 47 serve to hold their associated plungers 27 in their upper or inoperative positions on drive member 26. It is noted that when a plunger 27 occupies its upper position the stop element 41 carried thereby will be disposed within opening 34 of disc-shaped member 29.

To support drive member 26 for rotative movement and to locate it on housing 15 so that first circular plate 28 lies in the plane of inwardly directed flange 22 of cover 17 there is provided a support member 48. Support member 48 comprises an annular body portion 49 from which outwardly laterally projects a camming portion 50 (whose purpose will later be described in detail) and upwardly from which projects a cylindrical portion 51. First circular plate 28, disc-shaped member 29, and second plate 31 of drive member 26 are afforded with central openings 52 which align in the assembly of these elements. When drive member 26 is rested upon upper

surface 53 of annular body portion 49 cylindrical portion 51 thereof extends through aligned openings 52 to project to the exterior of housing 15. Drive member 26 in resting upon annular body portion 49 is adapted to 5 rotate about cylindrical portion 51 upon the application of manual force thereto. To prevent drive member 26 from vertically moving off of cylindrical portion 51 there is provided a suitable retaining washer 54 carried by an appropriate groove 55 afforded in the wall surface of cylindrical portion 51.

Associated with drive member 26 are a pair of spring pressed detent balls 56 for use in maintaining member 26 against free inadvertent movement relative to its support 48. These detent balls 56, together with their 15 springs, are disposed in recesses 57 provided in the upper surface 53 of annular body portion 49, and are biased outwardly normally to extend into openings 58 provided in the second circular plate 31 of drive member 26.

To properly position and hold support member 48 20 which carries drive member 26 there is formed generally centrally on base 16 of housing 15 a boss 61. Boss 61 includes an annular body portion 62 upon the upper surface 63 of which is formed a pair of generally semi-circular upwardly projecting portions 64 having their straight 25 surfaces 65 in opposition and with a space 66 therebetween. A circular guide plate 67 having a central opening 68 is fitted about semi-circular portions 64 and rests upon upper surface 63 of boss 61. Support member 48 in turn rests upon guide plate 67 and both support member 30 48 and guide plate 67 are fixed to boss 61 by screws 69.

Annular body portion 49 of support member 48 is provided with an annular recess 71 which receives semi-circular portions 64 to provide for an interfitting engagement 35 between support 48 and boss 61.

Circular guide plate 67 which rests upon surface 63 of boss 61 is provided with a series of slots or notches 72 about its periphery to effect a plurality of circularly arranged teeth-like portions 73 which are adapted to extend into transverse slots 44 in plungers 27 for a purpose to be described. The number of notches 72 provided correspond to the number of plungers 27 used in the present device.

Associated with support 48 and boss 61 is a correction 45 assembly 74 which serves to move stop elements 41 back into their recesses 43 in plungers 27 when it is desired to reverse an operation as will be later fully described. Correction assembly 74 comprises a vertically movable annular plate 75 and a pull member 76. Annular plate 75 has a central opening 77 which is divided by a strip 78 extending diametrically across opening 77 and being depressed so that it lies disposed somewhat below the main portion of plate 75. As shown in the drawings, plate 75 is provided with a depression or dimple 79 within which 50 camming projection 50 provided on support member 48 will nest when plate 75 is raised upwardly by pull member 76 in a correction operation.

Annular plate 75 of correction assembly 74 when in position has the circular portion thereof fitted about annular body portion 49 of support member 48. To accommodate strip 78 of plate 75 body portion 49 is provided with transverse slots 81 extending from central recess 57 thereof. When semi-circular portions 64 are disposed within recess 57 these transverse slots 81 will be 60 disposed at either end of space 66 provided between semi-circular portions 64 thereby to form in effect one continuous channel within which strip 78 fits and may move in a vertical direction.

As stated, correction assembly 74 includes a pull member 76. Pull member 76 is provided to effect the desired 70 vertical movement of plate 75 and comprises a rod 82 having a knob 83 at one end and having its opposite end cut-down in diameter and externally threaded as at 84. Rod 82 extends through a central opening provided in body portion 49 of support member 48 to project its

threaded lower end 84 into space 66 between semi-circular portions 64. Connection of pull member 76 to plate 75 is made by passing threaded lower end 84 through a suitable opening in strip 78 and attaching a nut 85 thereto.

To maintain annular correction plate 75 and pull member 76 in their lower or inoperative positions there is provided a spring 86. As shown in Figure 2, spring 86 is accommodated within space 66 and within a recess 87 afforded in annular body portion 49 of support member in vertical alignment with space 66. Spring 86 is disposed in surrounding relationship to rod 82 and has its lower end positioned on strip 78 and its upper end bearing on the interior end surface of recess 87 and exerts its bias downwardly against strip 78 normally to hold correction plate 75 in its inoperative position. Vertical movement upwardly of correction plate 75 is effected by pulling on pull member 76 which compresses spring 86.

As stated hereinabove, the present embodiment of the invention embodies twelve individual counters 12 and a summing counter 13, the number of individual counters corresponding to the number of lengths of lumber which it is desired to keep count of with this particular embodiment.

The details of the specific construction of the counters employed herein will not be given as they form no part of the invention. It is contemplated that any suitable commercially available counters may be employed.

The counters 12 are self-contained units of conventional construction and preferably are all alike. Each counter 12 comprises a casing 91 within which is disposed a plurality of counter wheels 92 including a units wheel, a tens wheel and a hundreds wheel, mounted on usual shafts and with appropriate interconnection whereby the units wheel is actuated first, and then tens wheel and thereafter the hundreds wheel. It is understood that a counter may be selected which embodies wheels of higher order should additional wheels be necessary to a particular type of counting operation. The various counter wheels are arranged in line and each counter has its peripheral face marked with the digits 0 to 9 spaced uniformly therearound in accordance with general practice. Casing 91 is provided with a suitable window or opening through which a single row of aligned numbers will be visible for reading the count computed on the individual counters 12.

The counters 12, as shown, are arranged in aligned order within housing 15, six at each side of actuator assembly 11. Suitable mounting brackets 93 are provided for the various counters 12, which brackets are connected by screws 94 to bosses 95 formed on base 16 to secure the counters 12 in place. Cover 17 of housing 15 has suitable openings 96 provided therein whereby the counter wheels 92 of the counters 12 are visible through the cover.

To effect operation of the counters 12 there is associated with each of such counters a drive assembly 97 comprising a rotatable drive wheel 98 having uniformly spaced peripheral teeth 99. Drive wheel 98 is adapted to be actuated by plungers 27 and is carried by a shaft 101 suitably journalled in openings provided in bosses 102 formed on base 16 of housing 15. A drive connection is effected between drive wheel 98 and its associated counter 12 through a usual flexible connection 103, which connection 103 is appropriately secured at one end to shaft 101 which carries drive wheel 98 and at its other end to the usual actuator shaft provided by the counter 12. Thus, when drive wheel 98 is rotated by plunger 27, as will be later fully described, this rotative movement is transmitted through flexible connection 103 to the actuator shaft of the associated counter 12 to advance the units counter wheel one digit.

The summing or totalizing counter 13 employed is understood to be of conventional construction, embodying a plurality of usual counter wheels 105 having the numerals 0 to 9 consecutively arranged on their peripheries.

In the present instance, to readily accommodate possible total count of high value of the individual counters 12 the summing counter 13 is afforded five counter wheels. Fewer or greater number of wheels, of course, could be employed dependent on the total count to be expected in a particular use of the present invention.

Summing counter 13 is suitably mounted upon base 16 of housing 15 at one side of counter actuator assembly 11 and, as shown, an opening 106 is provided in cover 17 to permit viewing of the wheels of counter 13 through cover 17.

To actuate counter 13 there is provided a rotatably mounted drive wheel 107 having uniformly spaced peripheral teeth 108. Drive wheel 107 is carried by a shaft 109 suitably supported by a bracket 111 mounted on a boss 112 provided on base 16. A usual flexible drive shaft 113 interconnects shaft 108 with the usual actuator shaft of counter 13 so that rotation of drive wheel 107 will effect rotation of the counter wheels of counter 13.

Drive structure 26 of counter actuator 11 is operatively connected to drive wheel 107 so that rotative movement of structure 26 results in rotative movement of drive wheel 107. This operative connection is supplied through disc-shaped member 29 of drive structure 26 which is pro-

vided about its periphery with uniformly spaced laterally extending teeth 114 which are adapted to mesh with the teeth 108 of drive wheel 107 so that rotation of drive structure 26 results in rotation of wheel 107. Rotation of wheel 107, as stated, effects actuation of flexible drive shaft 113 to operate summing counter 13. There are ten teeth 108 provided on drive wheel 107 and the driving relationship between drive wheel 107 and disc-shaped member 29 is such that drive wheel 107 is adapted to be moved one-tenth of a revolution by each tooth 114 of disc-shaped member 29 so that each such movement of drive wheel 107 will move the units counter wheel of summing counter 13 one digit. A sufficient number of teeth 114, of course, are provided on disc-shaped member 29 to accommodate the value of the shortest to the longest length of lumber to be handled by the present device. Thus, if a two-foot length is being counted drive wheel 107 will be engaged by two of the teeth 114 on disc-shaped member 29 to be twice actuated one tenth of a revolution to effect a two digit change on summing counter

13 and if a twenty-four foot length is being counted then, obviously, drive wheel 107 will be actuated twenty-four times by the teeth 114 to effect a corresponding change in the total count appearing on summing counter 13.

After a counting operation has been effected the counters 12 and summing counter 13 are, of course, returned to their zero positions. The conventional counters here contemplated for use in the present invention have a usual resetting construction whereby on reverse movement, which may be of the order of one revolution, all of the counter wheels of each counter are returned to zero. For convenience, all of the counters 12 and summing counter 13 are returned to their zero positions at the same time. To this end the reset arrangement 14 is provided. Reset arrangement 14 may comprise a plurality of rotatively mounted shafts 116 appropriately geared together for common movement upon operation of a reset knob 117. Each of the conventional counters 12 includes a reset gear 118 carried by a shaft projecting from the casing 91 of each counter, which reset gear 118 may be of the spur type. Summing counter 13 is, of course, also provided with a reset gear 119. Suitable gears 120 are appropriately positioned on the reset shafts 116 for cooperation with the reset gears 118 of the various counters 12 and a gear train 121 cooperates with reset gear 119 of counter 13, whereby on common rotative operation of the shafts 116 by reset knob 117 these counters will all be returned to their zero positions. This invention is not concerned with the particular form of reset arrangement utilized, any suitable reset means may be employed, the objective sought is only that there be

provision for clearing the counters to permit the performing of successive counting operations, in each instance starting from zero.

As stated hereinabove, the present embodiment of this invention has been described in connection with its use for the counting of lumber. It will provide a separate count of the number of pieces of lumber of the same length placed in a load while simultaneously providing an indication of the total lineal feet of all of the pieces of lumber of all lengths.

In the use of the present device in a load counting operation, the operator will first insert his finger or a suitable instrument into an opening 33 of counter actuator 11 which is positioned adjacent that number on annular flange 22 of cover 17 which corresponds to the length of the piece of lumber to be counted. In this action, he will apply a downward force to the plunger 27 which projects into that opening to depress this plunger against the bias of its spring 47, plunger 27 being properly guided in its downward movement by the aligned slots in guide plates 31 and 67. In this movement downwardly of plunger 27 under the force applied to it projection 46 thereof will engage a tooth 99 of the drive wheel 98 disposed therebelow to rotate such wheel and thereby actuate through its flexible shaft 101 the counter 12 associated with that drive wheel. As stated hereinbefore there is a drive wheel 98 associated with each of the counters 12. Each drive wheel 98 is interconnected with its counter 12 through its flexible shaft 101 so that when the drive wheel 98 is turned by the projection 46 of a plunger 27 a change of one number will be made in the count on the counter. As shown, one drive wheel 98 is disposed generally directly below each of the numerals, except for the zero, appearing upon annular flange 22 of cover 17. The drive wheel 98 disposed below numeral 2 of flange 22 is, of course, connected to drive the counter 12 identified with numeral 2 on cover 17, the drive wheel 98 associated with numeral 4 on flange 22 connects with the counter 12 identified with numeral 4, and so on with each of the drive wheels 98.

After an operator has actuated a plunger 27 and this action has been registered on its associated counter 12 he releases pressure from the plunger. However, this plunger does not return to its original position even though spring 47 exerts its bias to move it upwardly. Its upward movement is stopped by the engagement of shorter leg 42 of resilient stop 41 with the under-surface of guide plate 31 of counter actuator 11.

After an operator has registered a piece of lumber on a counter 12 he next must register the lineal footage of that piece upon summing counter 13. To do this, he keeps his finger in the same opening through which he actuated the plunger 27 and rotates drive structure 26 of counter actuator 11 clockwise until his finger strikes finger stop 25. In this rotative movement, plunger 27 which was actuated is bodily carried away from the drive wheel 98 which it had operated. Stop 41, which prevents plunger 27 from entering its opening, so positions plunger 27 that the slot 44 in its body portion 36 will accommodate and permit the teeth 73 of guide plate 67 to be passed. Teeth 73 also cooperate with slot 44 to hold plunger 27 level and steady in this rotative movement.

As the operator rotates drive structure 26 laterally extending teeth 114 of disc-shaped member 29 engage with and move drive wheel 107 which is associated with summing counter 13. The number of teeth 114 which engage drive wheel 107 corresponds to the length of the piece of lumber which had been registered on counter 12 and drive wheel 107 will be moved that many times. Thus drive wheel 107 will through its flexible shaft 113 operate summing counter 13 a number of times equal to the length of the piece of lumber.

As stated hereinbefore body portion 49 of support member 48 is provided with a camming portion 50.

Camming portion 50 projects in the path of travel of stop 41 carried by a rotatively displaced plunger 27 and is so located within housing 15 that as the operator's finger nears the zero position at finger stop 25 stop 41 will strike camming portion 50 and be moved thereby to be pressed in the direction of face 39 of the plunger to move its shorter leg 42 into its recess 43 thereby disengaging it from guide plate 31. After the operator has reached the zero position at finger stop 25 he removes his finger. Thereafter, since plunger 27 is no longer restrained by stop 41 it will move upwardly under the force of its spring 47 into its normal position relative to counter actuator 11. Now, the counting device 10 is ready for the next counting operation. It is noted that it is not necessary to return the plunger 27 which had been actuated to its original position relative to the drive wheel 98 which it had operated, another plunger 27 now occupies that original position. Thus, if a piece of lumber of the same length is next to be counted the operator need only actuate the plunger 27 which is now associated with the number on flange 22 which corresponds with the length of such piece of lumber. After each complete counting operation, therefore, the present device will be in position for immediately effecting the count of another piece of lumber.

Correction means are provided in the present device to care for a situation where an operator inadvertently starts to register a piece of lumber wrongly; for instance, he may depress a plunger 27 to indicate a 10 foot length when he had intended to register an 8 foot length and he may have started a rotative operation of counter actuator 11. In such case, the operator will reversely rotate counter actuator 11 so that teeth 114 thereof will operate drive wheel 107 in reverse direction to remove the count which was placed on summing counter 13. Then he will pull on knob 83 of pull member 76 to lift correction plate 75 to abut it against the under-surface of plate 31 of drive structure 26, camming projection 50 nesting within depression 79 to permit this lifting. Correction plate 75 in this upward movement will engage the stop member 41 holding down the plunger 27 which was erroneously depressed to return its shorter leg 42 into its recess, whereupon spring 47 of the plunger will return it to its normal position. In this return movement projection 46 of the plunger moves drive wheel 98 backwardly to correct the count on counter 12. The operator will then release his hold on knob 83 and spring 86 will return correction plate 75 and pull member 76 to their inoperative positions.

Obviously, the operator could, if desired, operate the correction plate 75 at any time if he wanted to be assured that all of the plungers 27 were in their proper starting positions prior to a counting operation.

After an operator has registered the number of pieces placed in a load and obtained a total lineal footage count on summing counter 13 he then returns all of counters 12 and summing counter 13 to zero to place the device in condition for the next counting operation.

With the present counting device it is readily apparent that the possibility of human error in counting the contents of a load is definitely greatly reduced. After an operator has obtained a tally of the numbers of the individual lengths of pieces of lumber and the aggregate lineal footage it is a simple matter for a clerk in the office to calculate the board footage by multiplying the aggregate lineal footage by a factor corresponding to the cross-section of the pieces of lumber which have been counted.

While a certain preferred embodiment of the invention has been specifically disclosed, it is understood that the invention is not limited thereto as many variations will be readily apparent to those skilled in the art and the invention is to be given its broadest possible interpretation within the terms of the following claims.

What we claim is:

1. Mechanism for counting individually a number of different items and for totalizing the aggregate value of the individual counts, said mechanism comprising a plurality of piece-counters corresponding in number to the number of different items to be counted, a totalizing counter, a plurality of drive means, each operatively associated with a single piece-counter, a plurality of independently operable members adapted to actuate selectively each of said drive means to operate each of said piece counters individually, an actuatable member supporting said plurality of independently operable members, means supporting said actuatable member for movement selectively relative to each of said plurality of drive means, said plurality of independently operable members being bodily displaceable upon said movement of said actuatable member to locate each of said independently operable members selectively in operative position relative to each of said drive members, and means providing an operative connection between said actuatable member and said totalizing counter for operation of the latter by the former on movement of said actuatable member relative to said drive means.

2. Mechanism for counting individually a number of different items and for totalizing the aggregate value of the individual counts, said mechanism comprising a plurality of piece-counters corresponding in number to the number of different items to be counted, a totalizing counter, a drive means for each of said piece-counters, means providing an operative connection between each of said drive means and its associated piece counter, a rotary support member, a plurality of independently operable members supported for rectilinear movement by said rotary member and each operable to actuate each of said drive means to operate said piece-counters individually, said plurality of independently operable members being bodily displaceable upon rotative movement of said rotary support member to locate each of said independently operable members selectively in operative position relative to each of said drive members, and means providing an operative connection between said rotary support member and said totalizing counter for operation of said totalizing counter on rotation of said rotary support member.

3. Mechanism for counting individually a number of different items and for totalizing the aggregate value of such individual counting, said mechanism comprising a plurality of piece-counters, one corresponding to each of said different items, a totalizing counter, a plurality of drive means, each operatively connected to a single piece-counter for actuation thereof, a rotary member, a plurality of manually depressible, independently operable, plungers slidably mounted on said rotary member, said plungers corresponding in number to the number of piece counters, each of said plungers being depressible to operate each of said drive means to actuate said piece-counters individually, said rotary member being movable to move said plungers for selective operation of each of said drive means, a drive means for said totalizing counter, and means providing an operative connection between said latter drive means and said rotary member whereby on rotation of said rotary member said totalizing counter is operated.

4. Mechanism for counting individually a number of different items and for totalizing the aggregate value of the individual counts, said mechanism comprising a plurality of piece-counters corresponding in number to the number of different items to be counted, a totalizing counter, a plurality of drive means, each operatively connected to a single piece-counter for actuation thereof, a rotatively mounted actuator member, means providing an operative connection between said rotative actuator member and said totalizing member whereby on rotation of said rotative member said totalizing member is operated, a plurality of manually depressible, inde-

pendently operable, plungers slidably mounted on said rotative actuator member, each of said plungers being depressible to operate each of said drive means to operate said piece-counters individually, stop means associated with each of said plungers to retain a plunger in its depressed position after a counter actuating operation, and means operative to automatically return the depressed plunger to its normal position upon operation of said rotative actuator member to actuate said totalizing counter.

5. Mechanism for counting individually a number of different items and for totalizing the aggregate value of such individual counting, said mechanism comprising a plurality of piece-counters corresponding in number to the number of different items to be counted, a totalizing counter, a drive means for each of said piece-counters, means providing an operative connection between each of said drive means and its associated piece counter, a rotary member, a plurality of independently operable members supported for rectilinear movement by said rotary member and each operable to actuate a drive means, to operate a piece-counter, said plurality of independently operable members being bodily displaceable upon rotative movement of said rotary member to position each of said independently operable members for actuation of each of said drive members to operate each of said piece counters individually, a drive means for said totalizing counter, and peripheral teeth on said rotary member adapted to operate said drive means for said totalizing counter to actuate the latter.

6. Mechanism for counting individually a number of different items and for totalizing the aggregate value of the individual counts, said mechanism comprising a plurality of piece-counters corresponding in number to the number of different items to be counted, a totalizing counter, a plurality of drive means, each operatively connected to a single piece-counter for actuation thereof, an annular, rotatively mounted, actuator member having peripheral teeth thereon, means including a drive gear for operating said totalizing counter, said peripheral teeth engageable with said drive gear for actuation thereof on rotative movement of said actuator member, a plurality of manually depressible, independently operable plungers slidably mounted on said rotative actuator member, each of said plungers being depressible to operate each of said drive means to operate said piece-counters individually, stop means associated with each of said plungers to retain a plunger in its depressed position after a counter actuating operation, and means operative to automatically return the depressed plunger to its normal position upon operation of said rotative actuator member to actuate said totalizing counter.

7. Mechanism for counting individually a number of different items and for totalizing the aggregate value of the individual counts, said mechanism comprising a plurality of piece-counters corresponding in number to the number of different items to be counted, a totalizing counter, a plurality of drive means, each operatively connected to a single piece-counter for actuation thereof, a rotatively mounted actuator member, means providing an operative connection between said rotative actuator member and said totalizing member whereby on rotation of said rotative actuator member said totalizing member is operated, a plurality of manually depressible, independently operable, plungers slidably mounted on said rotative actuator member, each of said plungers being depressible to operate each of said drive means to operate said piece-counters individually, stop means associated with each of said plungers to retain a plunger in its depressed position after a counter actuating operation, means operative to automatically return the depressed plunger to its normal position upon operation of said rotative actuator member to actuate said totalizing counter, and correction means independently operable to return an actuated plunger from its depressed position.

8. Mechanism for counting individually a number of different items and for totalizing the aggregate value of the individual counts, said mechanism comprising a plurality of piece-counters corresponding in number to the number of different items to be counted, a totalizing counter, a plurality of drive means, each operatively connected to a single piece-counter for actuation thereof, a rotatively mounted actuator member, means providing an operative connection between said rotative actuator member and said totalizing member whereby on rotation of said rotative actuating member said totalizing member is operated, a plurality of manually depressible, independently operable, plungers slidably mounted on said rotative actuator member, each of said plungers being depressible to operate each of said drive means to operate said piece-counters individually, stop means associated with each of said plungers to retain a plunger in its depressed position after a counter actuating operation, means operative to automatically return the depressed plunger to its normal position upon operation of said rotative actuator member to actuate said totalizing counter, and correction means independently operable to return an actuated plunger from its depressed position, said correction means comprising a bodily displaceable plate member engageable with said stop means for movement thereof to release said depressed plunger.

9. Mechanism for counting individually a number of different items and for totalizing the aggregate value of such individual counting, said mechanism comprising a plurality of piece-counters corresponding in number to the number of different items to be counted, a totalizing

5 counter, a drive means for each of said piece-counters, means providing an operative connection between each of said drive means and its associated piece counter, an annular, rotatively mounted, actuator member having peripheral teeth thereon, means including a drive gear for operating said totalizing counter, said peripheral teeth engageable with said drive gear for actuation thereof on rotative movement of said actuator member, a plurality of manually depressible, independently operable, plungers slidably mounted on said rotative actuator member, each of said plungers being depressible to operate each of said drive means to operate said piece-counters individually, spring-biased stop means positioned on each of said plungers adapted to retain a plunger in its depressed position after a counter actuating operation, means operative to return automatically the depressed plunger to its normal position after operation of said rotative actuator member to actuate said totalizing counter, and correction means independently operable to return an actuated plunger from its depressed position, said correction means comprising a bodily displaceable plate member engageable with said stop means for movement thereof to release said depressed plunger.
